GUESSING GAME BOARD

Phyllis Frederick, Plainfield, and Dermot F. Sims, Piscatawa, N.J., and Charles R. Zimmerman, Los Angeles, Calif., assignors to Mattel, Inc., Hawthorne, Calif.

Filed Feb. 26, 1970, Ser. No. 21,652

Term of patent 14 years

Int. Cl. D21—01
U.S. Cl. D34—5

FIG. 1 is a perspective view of a guessing game board showing our new design;

FIG. 2 is a top plan view thereof;

FIG. 3 is a front elevational view thereof;

FIG. 4 is a rear elevational view thereof;

FIG. 5 is a side elevational view thereof; and

FIG. 6 is a bottom plan view thereof.

We claim:

The ornamental design for a guessing game board, substantially as shown.
